UNITED STATES PATENT OFFICE.

PATRICK J. BOLEN, OF WICHITA, KANSAS.

MILK-STRAINER.

1,168,151.

Specification of Letters Patent. Patented Jan. 11, 1916.

Application filed September 28, 1915. Serial No. 53,107.

To all whom it may concern:

Be it known that I, PATRICK J. BOLEN, a citizen of the United States, residing at Wichita, in the county of Sedgwick and State of Kansas, have invented certain new and useful Improvements in Milk-Strainers; and I do hereby declare the following to be a full, clear, and exact description of the invention, such as will enable others skilled in the art to which it appertains to make and use the same.

This invention relates to filters, and more especially to strainers; and the object of the same is to produce a compound strainer for use on fresh milk. The invention comprises a plurality of strainers containing cotton or cotton flannel, and an element beneath the lower strainer also containing the same material and over which the milk has to flow in its passage out of the device. Details are set forth in the following specification and shown in the drawings wherein—

Figure 1 is a central vertical section of this device complete, and Fig. 2 is a perspective detail of one element removed.

Referring to the drawings, the numeral 1 designates a funnel having an ample cylindrical spout 2 closed across its bottom at 3 by the bottom of a cup 4 whose wall rises to the point 5 and is spaced from the spout to produce an annular outlet 6 around the lower end of the latter; and within said spout are removably located the four strainer elements. Just above its lower end the spout is provided with an annular series of slots 7 and intervening holes 8 for a purpose yet to appear. Within said spout is disposed a series of elements whereof four are shown in the accompanying drawings. The lowermost is what might be called a catching element.

It comprises a collar or ring 10 resting on the bottom 3 and having an inturned flange 11 around its upper end which stands below the slots 7, and across this flange is stretched a screen 15 of rather coarse mesh. This element contains cotton or cotton flannel 19 confined within the collar and between the screen 15 and the bottom 3. The elements above the catching element may be called straining elements. The one next above it comprises a metallic cylinder or collar 20 with inturned flanges 21 and 22 around its upper and lower ends, and the former is covered with a screen 25 of medium mesh. Above the lower flange 22 is an annular series of holes 28, interspersed

with notches 27 so disposed that they will register with the slots 7 when the holes 28 register with the holes 8 in the spout, and this will occur when the lower flange 22 rests on the upper flange 11 of the lowermost element. Within the collar 20 and beneath the strainer 25 is cotton or cotton flannel 29. The third element is a cylinder or collar 30 having inturned flanges 31 and 32 at its upper and lower ends and a strainer 35 of medium mesh across its upper end, beneath which is cotton or cotton flannel 39; and the lower flange 32 rests on the upper flange 21 of the second element. The fourth element is a collar or ring 40 having an inturned flange 42 around its lower end which rests on the upper flange 31 of the third element, and an out-turned flange 41 at its upper end which rests on a shoulder 9 formed within the lower end of the funnel 1 and uniting it with the upper end of the spout 2; and at the upper end of this element is a strainer 45 of quite fine mesh, which I preferably make conical as shown. This element may have an arched handle 46 which can be reached from above for lifting the element out of place, and beneath the strainer is cotton or cotton flannel 49.

I provide a suitable tool (not shown) for reaching down through the funnel and engaging the strainer of each element, when the upper element is removed, so that the elements beneath it can be lifted successively out of place or the second element can be adjusted by turning it on its axis until its openings register more or less completely with those in the spout.

All parts of this device are of metal, so treated that it will not rust, and the cotton or cotton flannel filtering material must be pure and clean and will be of a proper density to filter the milk without unduly retarding its passage through the device.

In use, the lower or catching element is inserted at the bottom of the column as shown, when its screen 15 stands below the openings 7 and 8; next the second element is inserted and pushed downward until it rests on the first element, after which it is turned so that its openings 27 and 28 register more or less accurately with those of the spout; then the third element is inserted and pushed down onto the second; and finally the fourth element or uppermost element is put in place, so that the whole device appears as shown in Fig. 1.

Fresh milk is now poured into the funnel, and if it is observed that it clogs the strainer, the uppermost element may be taken out of place temporarily and the 5 third element lifted so as to loosen up the filling 39. The cylinders or collars 20 and 30 will fit with some friction within the cylindrical spout, and as the weight of the parts is negligible they will doubtless 10 remain in their adjusted positions. The fine strainer 45 takes out all extraneous matter that may fall into the milk, and the various 15 layers of filling will strain out sediment, fibers, broken tissues, slime, and blood; and this strainer is especially efficacious if the 20 milk be chilled and passed through it a second time. After passing down through the three strainer elements and saturating the filling in the lowermost, the milk flows 25 radially outward over said lowermost element which therefore serves more as a catcher than as a strainer. With the parts made of ample size, the strainer will clean about forty gallons of milk without replacing the filling, but from time to time the various elements must be removed, and the 30 cotton filling replenished. Obviously the upper element where the filling will not be packed at all densely, will take out the coarsest particles, the third element the 35 next coarsest, and the second element the finest; and at the bottom of the column the strained milk saturates the filling in the lowermost element, and thereafter flows 40 down onto it and over it (but not through it) in its passage radially through the registering openings to the cup. Within the channel 6 in the latter the strained milk rises until it flows over its upper edge 5, 45 and this device is all ready to be set into a milk can or receptacle to catch the milk. In large dairies where there is much milk 50 and the strainer is in constant use, it may be well to provide two sets of elements so that an operator can be cleaning one set 55 and replacing its filling while the other set is in use, and the substitution will take but a moment. It will be observed that bottom 60 3 of the cup serves as the bottom of the lowermost element, and the strainer at the top of this element serves as the bottom of the one above; in other words, each element is open at the bottom and closed at the top excepting for the lower flange, and the 65 upper flange and wire gauze of each element constitutes the bottom of the element above when they are assembled in the column. The lower flanges will be of sufficient width to hold the loose filling in 70 place when the several elements are inverted, but should not be wide enough to interrupt the filtering or straining process.

What I claim is:

Copies of this patent may be obtained for five cents each, by addressing the "Commissioner of Patents, Washington, D. C."

1. In a milk strainer, the combination with a funnel whose spout has its lower end closed and its wall provided with an annular series of openings on a line above said lower end; of a series of independent filtering elements removably disposed within said spout, the lowermost having a series of openings adapted to be thrown into register with those in the spout, and a catching element resting on said bottom and supporting said lowermost filtering element. 75

2. In a milk strainer, the combination with a funnel whose spout has its lower end closed and its wall provided with an annular series of openings on a line above said lower end; of a series of independent filtering elements removably disposed within said spout, the lowermost having a series of openings adapted to be thrown into register with those in the spout, and a catching element resting on said bottom 85 and supporting said lowermost filtering element, each of said elements including a collar fitting removably within the spout, a screen across its upper end, and a filling of cotton. 90

3. In a milk strainer, a funnel having a cylindrical spout with lateral outlets through its wall near its lower end, and a cup whose bottom closes the lower end of the spout and whose wall surrounds that of the spout and rises above its openings; combined with a catching element seated in the spout beneath said openings and resting on said bottom, and a series of filtering elements in the spout above said catching element and respectively above each other, the lowermost having openings adapted to register with those in the spout and each element containing a filling of filtering material. 100

4. In a milk strainer, the combination with a funnel, a cylindrical spout having radial openings near its lower end and an out-turned shoulder at its upper end uniting it with the smaller end of the funnel, 110 and a cup whose bottom closes the lower end of the spout and whose wall rises around its openings; of catching element in the spout beneath its openings and resting on the bottom of the cup, a series of filtering elements in the spout above the catching element, flanges at the upper and lower ends of said elements adapted to contact with each other, and an uppermost filtering element having an inturned flange at its 120 lower end, an outturned flange at its upper end adapted to rest on said shoulder, and a handle. 115

In testimony whereof I affix my signature.

PATRICK J. BOLEN.
